UNITED STATES PATENT OFFICE.

CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT.

MACHINE FOR DOUBLING, WINDING, AND MEASURING CLOTH.

Application filed December 19, 1927. Serial No. 240,948.

This invention relates to machine for winding, measuring and doubling cloth and is intended to provide a machine capable of easy and quick threading by the operator 5 from his position in front of the machine and which shall be capable also of securing a perfectly wound package of either single or doubled cloth with even edges at the ends, while running the machine at higher 10 speeds than heretofore has been the practice. The machine is also perfectly adapted to be operated for cloth inspection purposes without loss of its other amenities.

Doubling and measuring machines as 15 hereintofore constructed and arranged have been needlessly wasteful of time in the operation of threading a piece of cloth into the machine besides involving considerable stooping and requiring the operator to go 20 around to the rear of the machine when threading in each piece of cloth. Moreover, in the prior art machines the shifting of the cloth in advance of its reaching the plicator and winder elements, not only 25 is the operator required to watch both the unwinding package and the plicator at the same time, but there is much greater likelihood of error in shifting too much or too little, thus requiring great skill to keep the 30 middle line of the cloth registering with the apex of the plicator. Such uneven shifting of the cloth results in package being wound having uneven edges at each end.

The present invention overcomes these 35 and other difficulties by providing a new arrangement of the cloth delivery means, the plicator and the winder, or package forming element, in such relationship that these difficulties are eliminated, as will be hereinafter explained and a machine capable of very 40 rapid action insuring perfect center line folding or doubling with the edges at each end of the package produced perfectly even with one another, and which can be very 45 rapidly and easily threaded with successive pieces of cloth. The cloth may also be measured and repackaged without doubling when desired.

In the accompanying drawings I have illustrated a preferred form of construction 50 and arrangement embodying the principles of this invention in which Figure 1 is a front elevation of a completely assembled

machine with a piece of cloth threaded 55 therein.

Figure 2 is a right hand elevation of the same machine.

Figure 3 is a left hand elevation of the same machine.

Figure 4 is a front detail view showing 60 a front elevation of the plicator and gripping or sword arm.

Figure 5 is a plan view showing the three angularly disposed arms of the plicator.

Figure 6 is a perspective view showing the 65 plicator bars and sword arm in their relation to a piece of cloth being doubled in order to illustrate the folding action of the plicator.

In the practice of this invention according to the form illustrated in the drawings, I provide a suitable frame work, or base, comprising the side uprights or standards 1 suitably spaced apart and secured together by proper tie-rods and which form a support for a horizontal oblong frame 2 mounted upon said standards and provided at its opposite end portions at front and rear with short track members 3 to support a transversely movable carriage, that is a 80 carriage that is movable transversely to the travel of the cloth.

The stationary frame of the carriage is provided with supporting bearing brackets, or arms, 1^a for supporting a beam of cloth 85 to be unwound and suitable guide rods or rollers extending from end to end of the stationary frame, as shown at 2^a, are used as guiding and tensioning means for the cloth.

Before passing to the plicator for the guiding and tensioning means, the cloth is shown passing around a measuring drum 30 with the back face of the cloth in contact with the frictional or roughened surface of 95 the drum.

The plicator is of the parallel plane type, that is the cloth approaching the plicator in open or full width position returns from the plicator in a doubled condition in a plane 100 that is parallel with the single or open breadth of cloth approaching the plicator.

This plicator comprises three angularly disposed bars or members, the topmost of which, numbered 7, is horizontal, meeting at 105 its inner end an obliquely inclined bar 8

lying in the same plane and inclined at an angle of 45 degrees to the horizontal plane, while the third bar lies at an angle of 45 degrees from the opposite side of the machine and joins the other two bars at their meeting angle or apex, but sufficiently spaced in a parallel plane to allow the two meeting portions of the cloth to pass between the plane of bar 7 and the plane of bar 9, as will be readily understood from an inspection of Figures 5 and 6.

As shown by the arrows indicating direction, the cloth travels upward in open or full width condition from the measuring roll 15 behind the plicator, with its medial line in registry with the apex of the plicator, one-half of the cloth therefore passes over and down the front side of the horizontal member 7 of the plicator, while the other half of the 20 cloth takes a quarter turn from behind, around the plicator member 8, whence it travels horizontally around the other diagonal plicator member 9 rearwardly and downwardly so that the finished faces of the 25 two portions of the cloth are folded together with their edges in registry with each other.

The plicator element is inclined forwardly for reasons presently to be explained. In front of the plicator is mounted a pair of 30 revoluble clamping or gripping jaws 10^b which grip the core board, on which the doubled cloth is to be wound, said jaws being carried by their respective shafts 10, which have splined engagement with their driving 35 elements and along whose axis the shafts are adjustable to accommodate the spacing of the jaws to the width of the package to be formed according to the width of the cloth being acted upon. To support the inner ends 40 of the longitudinally adjustable shafts 10 of the winder element I provide adjustable bearing members 19 which are provided with supporting bearings at their upper end and which are carried by sleeves 19^a mounted to 45 slide on spaced apart bars, or track rods 19^b.

It will be understood that the winding element thus described forms the energizing member for drawing the cloth through the machine. It may be driven by any convenient mechanism, but I have here shown 50 an electric motor 12 having speed reducing gearing connections 13 and 14 by which a counter shaft 17 is driven from which rotative movement is imparted to the aligned 55 winder shafts 10 by means of sprocket chains 10^a connecting sprocket wheels on the respective shafts, the sprocket chains acting to secure uniform rotation of the two aligned jaw shaft or winder shaft elements.

60 While the measuring drum 30 and the cloth guiding and tensioning means are mounted in the stationary frame, it will be seen that the plicator element, as well as the winder element, are mounted in a movable 65 carriage or frame 6 of general oblong shape

supported by the four grooved wheels 4 resting upon the track members 3, shaft 5 passing through the track wheels 4 at one side of the machine carrying a pinion 50 intermeshing with a rack bar 51 secured to the 70 stationary frame 2 of the machine. On each end of the shaft 5, which may be termed the carriage actuating shaft, there is placed a hand wheel 5^a by which the operator can shift the plicator and winder unit, or carriage, transversely in either direction. Stops 75 3^a at each end of the track serve to prevent running the carriage off the frame.

The mounting of the winder element and the plicator element to move in unison is of 80 great practical importance. It will be seen that with the plicator frame directly in front of the operator, the two edges of the doubled portion of the cloth are directly in line with his vision and, furthermore, should be in 85 alignment or registry with the upwardly moving full breadth of cloth before it passes over the plicator. By merely keeping his eyes on the doubled edges of the cloth and seeing that they align with the upwardly 90 advancing portion of the cloth, the operator has an absolutely certain and positive guide for maintaining the folding line exactly at the middle line of the cloth. Furthermore, since the winding element and the plicator 95 are positioned in fixed relation to each other, it necessarily follows that so long as the two doubled edges and the upwardly moving single edge at the right hand side of the cloth are in registry, the doubled portion of the 100 cloth must necessarily wind evenly on the winding reel so that perfectly even edges are formed at each end of the wound package, a thing that was very difficult of attainment where the plicator was fixed and the cloth 105 before approaching the plicator was shifted transversely in the attempt to secure proper alignment or registry between the middle line of the cloth and the apex of the plicator element.

The plicator is preferably set at an angle of about 60 degrees to the horizontal, being inclined forwardly toward the operator. The arrangement is such that the operator can easily reach every portion of the machine 115 from his operating position in front when threading the cloth through the machine. He needs merely to pick up the loose end of the cloth, whether it be in a roll on a beam, or whether it be folded in pleats in a tray 120 resting on the floor at the bottom of the machine, can then readily pass the forward or free end of the cloth around the guiding and tensioning members 2^a, which may be smooth bars or rollers, around the measuring 125 drum 30, up over the back of the plicator frame, whence it is drawn around the plicator members or bars in the manner illustrated and then carried to the winding reel. Preferably the cloth passing from the plica- 130

tor to the winding reel, passes under a tensioning roller 25 mounted in a swinging frame 24 which serves as an equalizer to compensate for the eccentricity of the revolving cloth package. Every portion of the cloth is within easy reach of the operator at the front of the machine and, as the loose end of the cloth can be very quickly and conveniently drawn through the different cloth engaging and guiding elements with the winding reel in front of the upwardly inclined plicator, a great saving in time in threading the machine is effected.

While the measuring apparatus per se forms no part of the invention herein claimed, it may be explained that the measuring drum shaft 31 is provided at one end with a small pulley 32 connected by a belt with an expandible pulley 33 of well-known type which by intermeshing pinions actuates a counter 34 which registers the yardage according to the number of revolutions of the cloth drum.

The machine may also be used for perch-
25 ing or inspecting the cloth and the forward inclination of the plicator is of great advan-
tage for this purpose, besides making the top of the plicator easily accessible to the operator for doubling purposes. When perch-
30 ing or inspecting the operator takes his position behind the machine where he can easily watch the registry of the doubled edges with the edge adjacent upwardly ad-
vancing open breadth of the cloth, while
35 the angle of inclination affords a perfect light for inspecting the cloth in its progress toward the top of the plicator. The hand wheel at the rear of the machine enables him to perfectly control the position of the plica-
40 tor and winder to maintain the desired reg-
istry between the edges of different portions of the cloth as above described. The ma-
chine, therefore, while in very compact form makes the most complete provision for sim-
45 taneously measuring, rewinding, inspecting and doubling the cloth. The sword arm 7
projecting between the planes of the plicator members 7 and 9 to the middle fold of the cloth in the usual and well-known man-
50 ner serves to maintain a correct creasing of the cloth along its medial line.

It will be understood that as the cloth advances toward the plicator from the tensioning and guiding means it tends to swerve
55 from side to side, particularly when the cloth is being rapidly run through the machine. In the prior art machines, the operator was constantly attempting to counteract this lateral movement of the cloth by shifting the cloth guiding means and in doing this it was necessary for him to watch the cloth guiding means and also the face to face edges of the doubled portion of the cloth where they converge or meet in the
60 plicator, which points being located at dif-
65

ferent positions made careful and instantaneous observation very difficult, so that much skill and intelligence was necessary to effect the accurate doubling of the cloth on medial line and the winding of an even
70 package. Indeed it was almost impossible to wind a package under those conditions, at any reasonable speed, whose ends should have its edges properly aligned or even with one another.

With the present arrangement, it is only required that the operator shall watch one edge of the upwardly advancing stretch of cloth, which is directly in front of his line of vision, so that he can readily maintain
80 the two registering edges of the doubled cloth coming from the plicator in line with the creasing edge of the upwardly advancing stretch of cloth with the result that the cloth coming from the plicator is easily kept
85 in line, or in registry, with the cloth leaving the plicator with its two edges in registry. In other words, there is ample time to shift the plicator and the cloth package so that the plicator is always handling the cloth in
90 perfect alignment with the medial line of the cloth where the fold ought to be made and, as the winder element follows the plicator in these shifting movements, the successive windings of the edges of the cloth will
95 lie perfectly even with one another. This permits the machine to be run at greatly increased speeds, thus largely increasing the capacity of the machine for work and economizing in the cost of measuring, winding
100 and doubling and inspecting. The time consumed in thus dealing with each piece of cloth is further shortened by reason of the fact that the arrangement of the different elements of the machine is such that the operator, after merely stooping to seize the free end of the cloth to be treated, can very conveniently and quickly thread this end through the machine, thus avoiding loss of
105 time in this part of the operation.

What I claim is:

1. In a cloth doubling machine the combination of means for guiding cloth being delivered, a parallel plane plicator mounted above said means, a winding element for receiving and winding the doubled cloth beyond the plicator, said plicator and said winding reel being freely slideable in unison by the operator transversely of the travel of the cloth while the machine is in operation, to enable the operator to maintain the alignment of the two folded edges of the cloth and of the corresponding end of the package being wound into registry with the edge of the cloth approaching the plicator.

2. In a doubling machine the combination with cloth guiding means secured in a stationary frame of a cloth doubling plicator and a revolute winder mounted in a movable carriage to be shiftable in unison with

each other in the direction of the rotative axis of the winder, whereby the winder and the plicator may be simultaneously shifted to follow the lateral swerving movements of the undoubled stretch of cloth approaching the plicator.

3. In a cloth doubling machine the combination of transversely arranged means for engaging and guiding the cloth to be doubled, a forwardly inclined transversely movable parallel plane plicator mounted above the level of said guiding means, a revoluble winding reel mounted forwardly of the lower portion of the plicator and being axially adjustable to position it in correct relation to the apex of the plicator and being also movable in unison with the shifting movement of the plicator when the machine is in operation.

4. In a cloth doubling machine the combination with a stationary frame and cloth guiding means mounted therein, a transversely movable carriage supported upon said frame, a plicator comprising angularly disposed turning members arranged in parallel planes mounted on said carriage, and an axially adjustable winding reel also mounted on said carriage in front of the lower portion of the plicator and a tension equalizer arranged to engage the doubled cloth as it approaches the winder.

5. In a cloth doubling machine the combination with a supporting frame having transverse cloth guiding means, a super-imposed carriage shiftable in either direction transversely of the travel of the cloth, a revoluble winder arranged on the forward part of the carriage, and a parallel plane plicator secured to the rear portion of said

carriage and extending upwardly and forwardly to overhang the winder while leaving exposed to the direct view of the operator the doubled edges of the folded cloth issuing from the plicator and affording also a view of one edge of the rear stretch of cloth passing upward behind the plicator, whereby the operator is enabled by comparison of the several edges to shift the plicator and winder to bring the doubled edges of the cloth in proper relation to the aforesaid back stretch of the cloth.

6. In a machine of the class described the combination with a supporting frame of cloth engaging and guiding devices, including a rotative cloth measuring drum mounted therein, a movable carriage, a revoluble winding reel mounted in said carriage to permit its axial movement in relation to said cloth guiding devices and an equalizing roll also mounted on said carriage to be shifted in unison with the winding reel when the machine is in operation.

7. The combination with a supporting frame of parallel cloth guiding devices including a revoluble cloth measuring drum mounted in said frame, a transversely movable carriage supported above said frame, a revoluble winding reel mounted in said carriage and an upwardly projecting parallel plane plicator secured to said carriage and an equalizer roll arranged to receive the cloth directly from either the plicator or from the cloth measuring drum for effecting proper delivery of the cloth to the winder, either in single or doubled stretch. 75

In witness whereof, I have subscribed the above specification.

CHARLES G. RICHARDSON.
